UNITED STATES PATENT OFFICE.

CHARLES W. BONER AND SAMUEL S. OSBORNE, OF RAYMONDVILLE, TEXAS.

VENDING MACHINE.

Application filed July 23, 1923. Serial No. 653,270.

To all whom it may concern:

Be it known that we, CHARLES W. BONER and SAMUEL S. OSBORNE, citizens of the United States, residing at Raymondville, 5 Willacy County, Texas, have invented a certain new and useful Improvement in Vending Machines, of which the following is a full, clear, and exact description, such as will enable others skilled in the art to 10 which it appertains to make and use the same.

Our invention relates to vending machines and more particularly to coin-controlled vending machines designed for dispensing 15 pencils, chewing gum, or similar objects or parcels.

An object of the invention is to provide a vending machine which will be positive and accurate in its operation and of few and 20 simple parts not easily broken or gotten out of order.

It is also desired to provide a device which may be operated only by a coin of the correct denomination and which may be quickly 25 and easily filled with objects to be dispensed when the supply becomes exhausted.

Referring to the drawing herewith wherein like numerals of reference are applied to like parts in all the views, Fig. 1 30 is a front elevation of the assembled device; Fig. 2 is a longitudinal section on the plane 2-2 of Fig. 1; Fig. 3 is a top plan view with one side broken away to show some interior parts; Fig. 4 is a rear elevation with 35 part of the casing broken away; Fig. 5 is a central longitudinal section of the operating mechanism on the plane 5-5 of Fig. 4; Fig. 6 is a front elevation of said operating mechanism.

40 The vending mechanism is housed in a casing which may be approximately rectangular in top plan as shown in Fig. 3. Said casing is mounted on a base 2 and has a front plate 1 with an opening 3 therein adjacent the base 2 to give access to the 45 delivering chamber 4. The rear side 5 is formed with an opening 6 therein to which access may be obtained to the coin chamber 8 normally closed by a locking plate 7 of any preferred construction. In Fig. 1 this 50 plate is shown as swinging on hinges 9 and locked by a latch 10.

The operating mechanism is mounted upon 55 a vertical plate 11 which is retained in slots 12 in the opposite sides of the casing. The upper end of said plate is bent rearwardly

at 13 to provide an attachment for two short perforated ears 14. About midway of said plate is an opening 15 formed vertically thereof to act as a guide for the plunger 17. 60

Secured on the forward side of the plate 11 are a number of plates 23, 24, 25 and 26, so shaped and spaced as to provide between them a vertical slideway 18 for the said plunger 17 which is of the same thickness as said plates and shaped to slide in the track 18. The upper end of said plunger has a push knob 19 thereon and the lower end is cut by a notch 20. At the left of said notch, as seen in Fig. 4, there is a 70 blunt shoulder 21, on the end of the plunger. The side of the said notch away from said shoulder is inclined at 22 to act upon a coin to force it into operative position.

The plate 24 is spaced from the side of the 75 casing sufficiently to allow a slideway 27 for the coin. This slideway is directed toward the center below said plunger by plate 25 so as to deliver the coin at a point directly below the plunger.

80 Between plates 23 and 26 is a slideway 28 in which fits a sliding latch plate 29 which is normally held forward into the passage 18 by means of a tension spring 30 secured at one end to a post 31 on the plate 25 and at its opposite end to the outer end of said latch. The forward end of the latch has an upper rounded shoulder 32 to contact with a coin 33.

85 Below the latch the slot 18 is inclined laterally to discharge the coin into the coin chamber 8.

90 The plunger 17 is held normally in elevated position, as shown in Figs. 2 and 4 by means of springs 34 on the forward 95 side of the plate 11 and secured to the ears 14 at their upper ends and at the lower ends within openings 35 in a delivering device. This device comprises a plate 36 slidable on the forward side of the plate 11 and connected to the plunger, and spaced from the plunger by means of a small plate 37 secured between the two plates by means of bolts and nuts 38 38. The lower end of the plate 36 is re-curved upwardly and is attached to the central portion of said plate at a point about midway thereof. The re-curved portion 40 is provided at a point about midway thereof with a groove 41 formed by bending said plate inwardly 100 against the plate 36, thus forming a delivering slot into which one of the objects to be

105

110

delivered may be received. As shown in Fig. 2 the objects to be dispensed in this device are lead pencils, 41'. These objects will just fit within the groove 41. They are delivered into said slot only in its elevated position by gravity.

Referring to Fig. 2 it will be noted that there is a diaphragm 42 about midway of the housing, inclined from the forward plate 40 downwardly so as to come into contact with the plate 40 at about the elevation of the groove 41. It is then extended vertically downward at 43 to prevent the delivery of said pencil before the plunger has been properly depressed.

On the rearward side of the plunger is a plate 44, which bears against the plunger, and the plates 23, 24, 25 and 26, and cooperates with said plates to form a side to the slots in which the plunger, the coin and the latch are adapted to operate. The plate is slotted centrally at 45 to allow the vertical movement of the nuts 46 upon the plunger.

In the operation of this device, the receptacle 46 for the objects to be delivered is filled, so as to furnish a sufficient supply of these objects. In the present case, pencils are shown. The force of gravity carries the pencils down so that one of them will be forced within the groove 41 in the plate 40, which, in turn, is secured to the plunger. This plate is held elevated by the springs 34, so that normally no pencil will be allowed to escape from the chamber. When it is desired to obtain a pencil, a coin is dropped downwardly in the slot 27 and, to admit the coin more readily, an upwardly extending flattened tube 47 is provided on the casing. The coin, which may be a nickel in case of pencils of this kind, is inserted in said tube, and will pass downwardly into the position shown in Fig. 4 immediately below the plunger. Attention may be called to the fact that when the nickel is not in position, the plunger will, on its downward movement, bring the shoulder 31 thereon into contact with the forward end of the latch 29, thus preventing the delivering of one of the pencils. When the coin is dropped into the position shown in Fig. 4 the downward movement of the plunger will act to bring the shoulder 22 of the notch 20 therein, against the coin in such a manner as to force it against the shoulder 32 upon the latch, and thus tend to wedge it backwardly out of the way of the plunger against the action of the spring, 30. The plunger will thus be allowed to pass the latch, and will force the nickel downwardly so that it may be discharged into the coin box 8. When the groove 41, containing the pencil, has moved downwardly below the lower edge of the wall 43, the pencil will be discharged upon the base 2 within the chamber 4, and may

be withdrawn through the opening 3 by the purchaser. When the plunger is released, the springs 34 will draw it back upwardly into its old position, and the latch 29 will be again thrown in so as to obstruct the passage of the plunger until another coin is inserted.

It will be obvious that this device is very simple and strong in construction, and will not easily get out of order. The device will be cheaply and economically made, and will positively deliver the object to be dispensed, at each movement of the plunger, after the coin has been inserted. The top 48 of the device may be provided with a lock, 49, holding it normally in locked position. It may, however, be removed by unlocking this lock, and when so removed, the plunger, together with the plate 11 and the operating mechanism thereon, may be withdrawn upwardly out of the groove 12 for examination, or repair, if necessary. When thus withdrawn, the whole interior of the box is available for cleaning, as desired. The further objects and advantages of this device will be apparent to one skilled in the art, without further description.

What we claim as new and desire to protect by Letters Patent is:

1. In a vending machine, a housing, a plurality of flat adjacent plates having therein a longitudinal plunger slot, a plunger therein, an inclined coin slot, and a laterally extending latch slot, a latch in said latch slot projecting into said plunger slot below said coin slot, said latch being adapted to stop said plunger, but being forced laterally out of said plunger slot by said plunger when a coin is inserted between the said plunger and latch, and a plate on said plunger having an object-receiving recess therein, said plate movable into delivering position when said plunger is depressed past said latch.

2. In a vending machine, a housing, a plurality of flattened plates having therein a plunger slot, a plunger therein, a latch projecting into said plunger slot normally acting to prevent forward movement thereof in said slot, means to deliver a coin between said plunger and latch whereby said plunger and coin may force said latch laterally when said plunger is depressed, and an object-delivering plate on said plunger, acting to dispense an object when said plunger is depressed past said latch.

3. In a vending machine, a housing, a plunger therein, means to hold said plunger in elevated position, a latch held resiliently in the path of said plunger, said plunger having a coin-receiving notch therein, by means of which a coin may be forced against said latch to move it laterally when said plunger is advanced, a plate on said plunger movable in a slot in said housing and having an article-receiving groove therein, on

its side toward the interior of said housing, means to deliver articles to said groove, whereby said article may be dispensed when said plunger is moved downwardly to de-

5 press said groove to a point below said slot.

4. In a vending machine, a housing, a storage chamber therein for cylindrical articles, a forwardly inclined lower wall therein, a plunger slidable vertically in the 10 forward side of said chamber and having an object-receiving recess therein, a latch normally holding said plunger from move-

ment downwardly into discharging position, an inclined slot leading to a point above said latch, whereby a coin may be inserted 15 below said plunger, said latch being adapted to be forced laterally by said coin when said plunger is moved downwardly.

In testimony whereof, we hereunto affix our signatures, this the 18th day of July, 20 A. D. 1923.

CHARLES W. BONER.
SAMUEL S. OSBORNE.
